UNITED STATES PATENT OFFICE.

JOHN K. TURAJSKI, OF CLEVELAND, OHIO.

SIPHON-FILLER.

SPECIFICATION forming part of Letters Patent No. 737,300, dated August 25, 1903.

Application filed May 23, 1903. Serial No. 158,557. (No model.)

To all whom it may concern:

Be it known that I, JOHN K. TURAJSKI, a citizen of the United States, and a resident of Cleveland, county of Cuyahoga, State of Ohio, have invented certain new and useful Improvements in Siphon-Fillers, of which I hereby declare the following to be a full, clear, and exact description, such as will enable others skilled in the art to which it appertains to make and use the same.

My invention relates to improvements in siphon-bottle fillers or devices for drawing aerated drinks of all kinds; and the objects of the invention are to provide a simple and efficient device for this purpose in which all overflow or waste is quickly carried away and in which the pressure by means of which the valve is opened is obtained by a simple mechanism not directly connected with the nozzle of the bottle itself, and hence more readily under the control of the operator. I obtain these advantages by means of the combination and arrangement of parts as hereinafter described, shown in the accompanying drawings, and specifically pointed out in the claim.

In the accompanying drawings, Figure 1 is a side elevation of a form of the device applicable to a refrigerator-wall and provided with a stem which is directly inserted therein. Fig. 2 is a longitudinal central section of the outer barrel, through which the liquid is drawn. Figs. 3 and 4 are side and edge elevations, respectively, of a modified form provided with a horizontal plate for attachment to the edge of a table or counter.

In the views, 1 is the outer barrel, which incloses the valve mechanism and which may be provided with any convenient form of attachment to the source of supply. The construction of the valve mechanism is clearly shown in Fig. 2, where 2 is the chamber into which the nozzle of the siphon is inserted, and 3 is the projecting mouth of the passage 4, which guides the fluid to the siphon-nozzle. This projection is tubular and adapted to be encircled by the nozzle, and a rubber washer 5 about the projection 3, against which the nozzle presses, serves to make a tight joint. A lining-sleeve 6 receives the overflow, if any, at the time the nozzle is removed and is forced against the base of the chamber 2 by

means of the nut 7, screwed upon the outer extremity of the barrel. An intervening washer is inserted between the nut and lining-sleeve. Perforations 9 about the sleeve 6 release the overflow or waste into the chamber 2, from whence it flows away through the passage 10 in the wall of the barrel 1. At the bottom of the barrel is formed the chamber 11, through which the outlet-passage 4 conducts the fluid through the nozzle of the siphon-bottle. A valve-seat 12 at the upper extremity of this chamber receives the valve 13, which is normally kept closed tightly by means of the spring 14, encircling a valve-stem 15 and inserted in the cylindrical recess 16, located in the back wall of the barrel 1. This spring presses against the rubber washer 17, which rests upon the shoulder 18 at the bottom of the recess 16 to prevent leakage about the valve-stem, and the spring engages the shoulder of the enlarged portion 19 of the valve-stem at its upper end. The valve is depressed to admit fluid through the outlet-passage by means of the lever 20, pivoted at 21 on the back of the barrel, and, as shown, the lever has one end inserted in a vertical slot 22 in the enlarged head of the valve-stem. When this lever is released, the spring-pressed valve will instantly seat itself and cut off the liquid flow. A washer 23 on the upper face of the valve engages the valve-seat and maintains a tight joint. It will be seen that while the lever is being lifted by the finger the thumb presses down upon the enlarged portion or head 19 of the valve-stem, thus making the action a very easy one.

In Fig. 1 the barrel is shown provided with a stem 24, which is inserted in the wall of the refrigerator and is secured thereto by means of the flange 25 on the outside of the wall and a nut 26, passed over the screw-threaded inner portion of the stem. The stem comprises the outer tube 24 and the inner tube 27, through which the fluid passes to the barrel. The tubes are connected together at either end and the overflow-passage for waste fluid passes continuously through the outer tube into the refrigerator, where it is discharged at the perforation 28. A nut 30 connects the barrel and its stem. In Figs. 3 and 4 is shown a device in which the valve is similarly operated; but in place of utilizing the

hollow stem 24 to support the cylinder it is provided with a horizontal flange 29, which can be readily attached to the under side of a table or counter. The overflow-passage then 5 extends straight down and discharges from its open extremity.

Having described my invention, what I claim as new, and desire to secure by Letters Patent, is—

- 10 In combination, in a siphon-filler, a barrel provided with upper and lower chambers, a central passage connecting said chambers provided at the upper end with a cylindrical extension or mouth adapted for insertion in the
- 15 nozzle of the siphon, a washer encircling said extension, a lining-sleeve in said upper chamber engaging said washer, a nut secured upon

the outer extremity of the outer chamber, a washer between said nut and lining-sleeve, overflow-passages in the sides of the lining-sleeve, an overflow-passage leading downwardly through the wall of the barrel from said upper chamber, a valve-seat in the lower chamber, a valve in the lower chamber, a spring for raising said valve against said seat, 20 and a device for depressing said valve to admit fluid into the passage connecting the chambers, substantially as set forth.

Signed at Cleveland this 14th day of May, 1903.

JOHN K. TURAJSKI.
